HIDE TREATING APPARATUS

Robert H. Griffin, Crestwood, Yonkers, N. Y., assignor to Tanners' Research Corporation, New York, N. Y., a corporation of Delaware

Application October 16, 1946, Serial No. 703,571

27 Claims. (Cl. 69—42)

1

This invention relates generally to the treatment of sheet material and more particularly to methods of and apparatus for automatically subjecting sheet material to a plurality of treatments as a continuous process. While the invention will be described for purposes of illustration as applied to the treatment of hides, it will be apparent that it is applicable to sheet material, generally.

In treating hides, skins, pelts and the like, hereinafter generally termed "hides" and especially in subjecting them to the so-called "beamhouse" operations or treatments of unhairing, scudding, cheeking and fleshing, it has heretofore been customary to perform each operation separately by hand or on suitable individual machines. Thus, each of these four operations is normally performed as a separate step requiring one or more individuals and the hides are carried manually or otherwise from one machine to the next until their treatment has been completed. When machinery is employed to perform these operations each machine is usually provided with a work-support in the form of a drum or similar means to which a hide is clamped mechanically as it is presented to the cutters or other working tools. Due to the irregular shape of hides, a considerable portion, sometimes as much as half of each hide, is enclosed in the mechanical clamps, requiring each operation to be performed in at least two stages, the second covering that portion of the hide held in the grippers during the first stage. These practices not only have made expenditures for equipment heavy, but have been extremely wasteful of manpower. As a result, several attempts have been made to devise means by which the treatment of hides can be made a continuous operation. While improvements over the separate step processes, none has succeeded in eliminating many of the disadvantages of the old practice.

An object of the present invention is to provide an improved method of and apparatus for subjecting hides and other sheet material to a plurality of treatments as a continuous process.

An additional object of the invention is to provide hide treating apparatus for automatically subjecting hides to a plurality of treatments in which each treatment is performed in a single stage and with a minimum number of parts of rugged construction.

A further object of the invention is to provide hide treating apparatus for subjecting hides to a series of treatments as a continuous process in which the hide engaging elements are auto-

10 matically adjusted, enabling the apparatus to handle hides of varying shapes and conditions without prior setting.

Another object of the invention is to provide a hide treating apparatus in which compensation is automatically made for variations in the thickness of each hide.

Other objects and features of the invention will appear hereinafter in the detailed description, be particularly pointed out in the appended claims and illustrated in the accompanying drawings in which:

Figure 1 is a front elevational view of an improved hide treating apparatus embodying the present invention, with portions removed to more clearly illustrate the details of construction.

Figure 2 is a side elevational view of the apparatus of Figure 1.

Figure 3 is a view on an enlarged scale of the central portion of Figure 2 with the cover of one of the vacuum chambers and other portions removed to more clearly illustrate the details of the mountings of the work-supporting drums and their associated treating devices.

Figure 4 is a side elevational view on an enlarged scale with portions removed of the end of the apparatus opposite that shown in Figures 2 and 3, illustrating certain of the details of the driving mechanism.

Figure 5 is a vertical sectional view on an enlarged scale taken along the lines 5—5 of Figure 1 showing certain of the details of construction of the first or lower drum and its associated structure.

Figure 6 is a vertical sectional view on an enlarged scale taken along the lines 6—6 of Figure 2 showing the details of construction of one of the cutter reciprocating mechanisms.

Figure 7 is a front elevational view on an enlarged scale of the lower section of the apparatus with portions removed to more clearly illustrate the construction and arrangement of the fluid jets and automatic cutter operating means associated with the first work-supporting drum.

Figure 8 is a vertical sectional view taken along the lines 8—8 of Figure 5, showing the details of construction of one of the work-supporting drums and its mounting.

Figure 9 is a schematic view of the hide treating apparatus.

Figure 10 illustrates diagrammatically an electrical and fluid pressure circuit for automatically controlling the work treating devices associated with either drum.

In the apparatus of the present invention the

hides or other sheet material to be treated are preferably carried on work-supporting drums while being presented to the treating devices by which the desired processing is obtained. Depending upon the nature of the treatments one or more supporting drums are employed and the hides are presented to one or several treating devices. The apparatus is especially suited for subjecting hides to a series of treatments as a continuous process. When so employed two or more supporting rolls are arranged in succession, each having a plurality of associated treating devices to which a hide is progressively presented, the hide being transferred from one roll to the next as it travels through the apparatus. In the embodiment of the invention shown for purposes of illustration, two supporting drums are employed, which with their associated working or processing devices, are adapted to treat both faces of a hide as it travels through the apparatus. While capable of other treatments the illustrated machine particularly lends itself to performing in a single pass of a hide the beam-house treatments of unhairing, scudding, cheeking and fleshing by which excess material is removed.

Referring now in detail to the drawings illustrating a preferred embodiment of the invention and in which like reference characters indicate like parts, the improved hide treating apparatus is provided with a suitable frame 1 having spaced, rigidly connected supports, uprights or ends 2. On the supports are carried the work-supporting or holding drums or rolls and their associated structures. Since the illustrated embodiment has but two such drums they will be designated hereinafter as the first and second drums, numbered 3 and 4, respectively. The supporting drums are rotatably mounted on the supports 2 through suitable bearings. The drums are arranged successively to carry the hide and expose its opposite faces to treatment as the hide passes through the apparatus. As illustrated, this may be accomplished by mounting the drums with their axes parallel and the second drum spaced above the first.

For introducing work into the apparatus there is provided a suitable inlet or feed mechanism, preferably in the form of a belt conveyor 5 mounted on spaced rollers or bearings 6. At its inner end the conveyor or feeder belt 5 is adapted to bear against or engage the first work-supporting drum 3. To enable the pressure exerted against the supporting drum to be varied, the inner rollers 6 are connected to suitable fluid pressure cylinders 7. Additionally the tension of the belt may be adjusted by use of suitable spacers 1a.

In performing in sequence the beam-house treatments or operations of unhairing, scudding, cheeking and fleshing for which the illustrated machine or apparatus is particularly designed, a hide, designated as 8, is placed hair or grain side down on the feeder belt 5, preferably with the hind shanks of the hide in the lead. The belt, travelling toward the first drum 3, delivers the hide to the drum to which the hide is then transferred. To correlate the preferred directions of movement of the belt and other working parts of the apparatus all such movements will be described hereinafter as if viewed from the near side of the apparatus as shown in Figure 2. So viewed the belt in moving toward the drum, travels in a clockwise direction. Since the first drum treats the hair side of the hide its surface moves in the same direction as the surface of

the belt 5 at the place of transfer, the drum thus rotating in a counterclockwise direction, and receiving the hide with the flesh or inner face of the latter against the outer face of the drum.

A particular feature of the invention is the means by which a hide or other work is gripped or held by the work-supporting drums. In place of the usual mechanical clamps the drums 3 and 4 preferably utilize suction as the gripping means, thereby enabling each drum to present an entire face surface of a hide to its associated treating devices. Such suction may be obtained by constructing the drums in the manner illustrated. Since the drums are identical in structure, only the first drum will be described in detail. As shown in Figure 8, each of the drums is desirably formed as a hollow cylinder, having a perforated or porous substantially cylindrical side or work-carrying wall 9, pierced or perforated by spaced holes, openings or perforations 10. At either end of the drum are trunnions, journals or shafts 11 and 12, respectively, which are journaled in and extend through bearings 13 carried by the supports 2. Of these shafts the shaft 11 is in the form of a hollow tube connecting the interior of the drum to a pump or other suitable exhausting means, not shown. Overlying the open end of the hollow shaft 11 is an air-tight exhaust chamber 14 having a bell or dome-shaped cover plate or casing 15 attached to the outside of the associated support 2, the chamber being connected to the exhausting means through suitable exhaust fittings 16. Appropriate sealing means such as gaskets 17 and 18 are interposed between the drum 3 and bearing 13 and the cover plate 15 and associated support 2, respectively, to make the connection air-tight. On the application of a partial vacuum or sub-atmospheric pressure to the interior of the drum by the exhausting means, suction is exerted on the drum's outer surface through the holes or openings 10, thereby gripping or holding the hide 8 to the drum with equal or uniform force over the entire area of the hide.

Positioned around the periphery of the first drum 3 in spaced stations are the treating devices by which a hide is unhair and scuddled. For this purpose there may be provided one or more, but preferably two, cutters or working tools rotatably mounted on the frame 1 and hereinafter termed the first and second cutters, numbered 19 and 20, respectively. These cutters are preferably bladed cylinders so positioned on the frame 1 that their working faces lie parallel to the face of the drum and extend substantially thereacross. The first cutter 19 is stationed somewhat beyond the feeder belt 5 and the second cutter 20 further around the periphery of the drum. The spacing between the cutters will vary depending upon the diameter of the drum and the sizes of the hides to be treated. For most efficient operation the spacing is such that slightly more than one-half the total length of a hide will pass beneath the second cutter while the hide is still passing the station of the first cutter. The cutters are rotated or driven by suitable means, and may be bladed in any manner satisfactory for performing the required unhairing and scudding operations, the preferred form being the herringbone-type shown in which sets of helical blades 21 are opposed at the center, enabling them to spread as well as cut the hide.

Since the cutters 19 and 20 extend substantially across the face of the drum 3, and are adapted to unhair a hide completely in a single

pass, provision is desirably made for uniformity of such treatment over the entire outer surface of the hide. For this purpose the work-carrying wall 9 of the drum is made resilient to enable it to accommodate itself to variations in the thickness of the hide being treated. The desired resiliency may be obtained by forming the wall of an outer section of rubber or like resilient material, bonded to and supported by an inner or backing plate or cylinder 22 of metal or other relatively rigid material. For wear resistance the resilient section may be formed of bonded layers of different consistency, the inner or pressure distributing portion or layer 23 being relatively porous and yielding and the outer or work-engaging layer or coating 24 being relatively hard and tough. So formed the work-carrying wall will accommodate itself to any irregularities in the hide and present an even level surface to the cutters, thus distributing the pressure of the latter equally over the entire hide and enabling the cutters to treat the hide uniformly.

Between the two cutters 19 and 20 is rotatably mounted a feeder in the form of a grip roll 25 of the usual type. As shown, the hide-engaging surface of the grip roll is preferably provided with opposed ridges or serrations, enabling it to spread the hide as the latter is fed to the second cutter 20. Both the grip roll and the feeder belt 5, by pressing the hide against the outer surface 9 of the first drum 3, also assist the suction means in holding the hide to the drum. Since its main purpose is to spread and feed the hide to the second cutter, the grip roll is rotated clockwise so that the adjacent surfaces of the roll and drum move in the same direction.

In addition to the cutters 19 and 20, the work treating devices associated with the first drum 3 also preferably include a series of sets of nozzles or jets 26 stationed at spaced intervals around the periphery of the drum and positioned to direct flat jets or sprays 26a of water or other fluid under pressure against the hide as it passes each jet station. While shown directed counter the direction of travel of the hide and substantially tangential to its surface, the jets may be directed either in or counter the hide's direction of travel and at various angles with its surface, depending upon the character of the hide and the nature of the treatment. Each set of jets may be mounted on and supplied fluid under pressure through a pipe or conduit 26b extending across the face of the drum between the supports 2. While any satisfactory arrangement of nozzles may be employed, that preferred is to position one set between the feeder belt 5 and the first cutter 19, sets between the first and second cutters on either side of the grip roll 25 and an additional set beyond the second cutter. In the illustrated embodiment the fluid jets act jointly with the cutters 19 and 20, to sever and remove the hair and other matter exposed to the cutters, and also drive or shear off scale and flush out hair follicles and other extraneous, excess or undesired matter from the pores of the hide, the pressure under which the jets are applied thus being at least sufficient to cause the jets to penetrate the surface of the hide. This joint action of the cutters and jets thoroughly and effectively scuds a hide coincident with its unhairing. While illustrated jointly with the cutters, the fluid jets 26a alone, usually under somewhat higher pressure, have been found an effective means of both unhairing and scudding. In such case, by varying the pressure to suit the

particular type of hide being treated, the flat high pressure fluid jets, impinging upon the hide, remove all extraneous matter, whether natural matter which is naturally bonded to or united with the hide, such as hair and scale, or foreign matter which has adhered to the surface of the hide, such as dirt and grit.

The spent fluid from the jets 26a is in part drawn into the drum and carried off through means suitably arranged to prevent accumulation of the fluid within the drum. For catching the balance of the fluid there may be provided appropriate means such as a catch basin 27 positioned to trap the spent fluid as it falls from the hide. Since the spent fluid contains hair as well as other valuable ingredients, it will normally be treated subsequently to recover its useful content as by-products, as well as to remove all foreign matter if recovery and recirculation of the fluid is desired.

As previously mentioned, the supporting drum 3 is adapted to rotate in a counterclockwise direction. Of the two cutters the second cutter 20 desirably rotates in a clockwise direction so that its surface adjacent or proximate the drum moves in the same direction as the confronting surface of the drum. The first cutter 19 is desirably reversible and adapted to rotate either clockwise or counterclockwise. In the preferred operation of the cutters the first cutter is made to rotate in a counterclockwise direction, its surface adjacent the drum and the corresponding surface of the second cutter thus diverging or moving away from each other. The advantage of this arrangement is that the cutters, when both are in engagement with the hide, will both stretch the latter, facilitating removal of the undesired matter from the surface, and by substantially balancing each other's force, will practically eliminate any resultant force affecting travel of the hide. To obtain such action during processing of the hide means are provided for causing the two cutters to act on the hide concurrently. For this purpose the cutters 19 and 20 are mounted on the frame 1 through housings 28 in which the ends of the shafts of the cutters are appropriately journaled. The journal housings 28, in turn, are slidably seated in jaws or guideways 29 formed in each of the supports 2 and so positioned as to enable the cutters to be reciprocated relative to and preferably radially of the drum while maintaining the axes of the cutters substantially parallel to that of the drum 3. This reciprocal movement is preferably obtained through fluid pressure actuation by connecting each of the journal housings 28 to one end of a piston or connecting rod 30, carrying at its other end a piston 31 slidably seated in a fluid pressure cylinder 32, the upper and lower ends of the latter being connected to a suitable source of fluid pressure, not shown, through fittings or other connections 33. By control of the fluid pressure means the cutters can then be caused to move toward and away from the drum at will, as well as to exert any desired pressure on the hide when in hide-engaging position. In the latter position the fluid pressure mounting also serves as a yieldable means or cushion, enabling the cutters to accommodate hides of varying thickness, and cooperating with the resilient work-carrying wall 9 of the drum to ensure uniformity of treatment of each hide. Yieldable or resilient mounting of the grip roll 25 is equally desirable and obtainable by supporting it on the frame through

a similar fluid pressure mounting or other suitable cushioning means.

Once a hide has been placed on the feed conveyor 5, provision preferably is made for automatic control of the apparatus in timed relation to the travel of the hide. This may be accomplished by use of photoelectric cells, switches, or like automatic control means positioned to be tripped by the hide and cause actuation of the treating devices as the hide is carried past their stations by the work-supporting drums. In the illustrated embodiment of the invention photoelectric cells are utilized for this purpose. While one cell located along the periphery of each drum intermediate its cutters would suffice, nicety of control is increased by employing two cells, both mounted on the inside of the frame 1 at one end of the drum, the first cell 34 positioned immediately following the first cutter 19, and the second cell 35 positioned in advance of the second cutter 20. The light sources 36 of the cells are mounted at the opposite end of the drum and are so arranged that their beams of light will pass freely across the surface of the drum to the associated cells only when the drum is unencumbered.

The two cells are connected through a control circuit 37 to the cutter reciprocating and driving means. A suitable electrical and fluid pressure circuit for each drum is shown in Figure 10. As there illustrated, each of the cells is connected through an appropriate amplifier 38 to a solenoid switch 39, the switches being arranged in series in the control circuit and held open so long as the cells are energized by the uninterrupted light beams. In the same circuit are four solenoids 40, each operating a three-way air valve 41, connected to an appropriate air pressure source. The valves are arranged in pairs, one pair of air valves 41a being connected to the upper ends of the cutter reciprocating fluid pressure cylinders 32 one of the illustrated spaced pairs of which is attached to either end of each of the cutters 19 and 20 and the other pair of valves 41b to the lower ends of the cylinders. The ports or sides of the two pairs of valves are reversed such that when the cylinders are connected to the air pressure ports of the air valves of one pair, their opposite ends are open to the exhaust ports of the other pair. In normal position, the solenoids 40 then being de-energized, the lower or inner ends of the cylinders are connected to the air pressure ports of the cutter releasing pair of valves 41b, and their upper ends to the exhaust ports of the cutter applying pair 41a. While the electric motors 42 or other actuating means by which the cutters are driven or rotated may be operated continuously through separate circuits, they are preferably connected, as shown, in the same circuit with the photoelectric cells 34 and 35.

With the above control circuit, the cutters 19 and 20 are normally held in released position away from the drum. As a hide is carried by the drum 3 it thus passes freely under the first cutter and thereafter interrupts the beam of the first photoelectric cell 34, closing one of the two switches 39 in the control circuit. After the leading edge of the hide has been engaged by the grip roll 25 and before it reaches the station of the second cutter 20, the hide interrupts the beam of the second photoelectric cell 35, closing the second of the switches 39 and completing the control circuit. The solenoids 40 are then energized, opening the air pressure ports of the cutter applying valves 41a, and the exhaust ports

of the releasing valves 41b, and causing the cutters to move in simultaneously and engage the exposed surface of the hide. Closing of the switches 39 actuates the cutter driving means 42 at the same time, causing the cutters to rotate and act upon the hide. If desired, suitable timing means can be interposed in the control circuit, enabling the cutters to be caused to act on the hide both simultaneously and at spaced intervals. As the hide continues in its travel around the drum 3 its trailing edge reaches and releases the beam of the first photoelectric cell 34, opening its associated switch 39 and, by de-energizing the control circuit, stopping the cutters and causing them to move away from the hide to released position.

Since, as previously pointed out, the first and second cutters 19 and 20 are stationed around the periphery of the drum, a distance less than one-half the length of the hide, each cutter, during its period of engagement with the hide, treats one-half of the hide's surface, the overlap not only ensuring treatment of the entire outer surface of the hide but covering the middle portion of the hide on which the most work is required. As the hide is always interposed between the cutters and the drum 3 when the cutters are in applied position, the fluid pressure cylinders 32 will afford a cushion, enabling the cutters to accommodate hides of different thickness without presetting of the spacing between the cutters and the drum. Thus, in addition to setting the speed of the motors 42, it is necessary only to set the fluid pressure sources to apply the most efficient pressure for a particular group of hides to render the operation of the cutters fully automatic. While described in connection with the cutters the same or a similar control circuit may be employed to control actuation of the fluid pressure jets 26a.

In the preceding portion of the specification there has been described that part of the mechanism of the hide treating apparatus by which a hide is unhaired and scuffed. The remaining treatments, cheeking and fleshing, are performed in the second phase of the process by the treating devices associated with the second work-supporting drum 4 as the latter carries the hide.

The second drum 4, constructed in the manner previously described for the first drum 3, is rotatably mounted on the supports 2, preferably with its axis parallel to that of the first drum and so positioned relative thereto as to engage the leading edge of the hide 8 after it passes the second cutter 20. Rotating clockwise, the second drum thereafter grips the grain or outer surface or face of the hide and presents or exposes the entire flesh surface of the hide to the associated treating devices.

Since the gripping force employed on both drums is suction, it is necessary to provide some means for releasing the force on the first drum to enable the hide to be transferred to the second drum. This can be accomplished by masking or blocking off from suction that portion or segment of the path of travel of the surface of the first drum in which the two drums are contiguous or adjacent. While a stationary slip shield or the like mounted within the first drum would suffice, such masking is readily accomplishable by mounting in the drum, stationarily relative to the frame 1, a pipe or tube 43 carrying jets 44 positioned to direct fluid jets or sprays 44a at that portion of the inner surface of the drum within the critical area of fixed or prede-

termined extent in which the transfer of the hide would be adversely affected by suction on the first drum. On operation of the jets, at a pressure sufficient to counterbalance or neutralize the suction within the drum over the critical area of separation, the hide is progressively released by the first drum 3 as it reaches the critical segment or area, enabling it to be gripped freely by the second drum 4. Since the jets 44a need operate only during actual transfer of a hide, a photoelectric cell or like means is preferably provided to limit their operation to that period.

The arrangement of the treating devices around the periphery of the second drum is similar to that employed for the first drum. As in the case of the latter, the second drum is provided with a plurality of rotatable cutters or tools, preferably two, which will be termed the third and fourth cutters and numbered 45 and 46, respectively. The relation between the stations of the third and fourth cutters is the same as that between the first and second cutters, peripherally, somewhat less than one-half the length of the hide to be treated, each thus being adapted to treat more than one-half of the total flesh surface of the hide. The relative directions of rotation of the third and fourth cutters are also the same, the fourth cutter being adapted to rotate counterclockwise and the third cutter in either direction and preferably clockwise. Similarly, the cutters 45 and 46 are fluid pressure mounted on the supports 2 and brought into engagement with the flesh side of the hide by photoelectric or other automatic control means, the fourth cutter being timed to engage the hide simultaneously with or in advance of the third cutter. A plurality of grip rolls 47 similar in construction and operation to the grip roll 25 are provided, one preferably being positioned in advance of the third cutter 45 and another intermediate the two cutters. The configuration of the blades of the cutters around the second drum will vary from that of the cutters around the first drum as necessary to perform the fleshing and cheeking operations. As in the case of the first drum, the second drum is preferably provided with jets 48 positioned to apply fluid sprays 48a under pressure against the flesh surface of the hide, the jets likewise being used either in conjunction with or in place of the cutters to completely cheek and flesh the hide, thus removing all extraneous matter as well as any foreign matter that may have become embedded in the surface of the hide.

Around the periphery of the second drum 4 beyond the fourth cutter 46 is the discharge means by which a processed hide is led from the apparatus. As illustrated, the discharge means may be in the form of a continuous belt conveyor 49 similar to the feeder conveyor 5 and likewise mounted on rollers 50 adapted to be adjusted by spacers to maintain the proper tension on the conveyor belt. To direct the hide from the second drum to the discharge conveyor there may be provided a wedge-shaped scoop 51 positioned to underride the hide after it passes the fourth cutter 46 and direct it to the discharge conveyor. To simplify the task of transfer from the second drum to the conveyor the critical transfer area may be blocked off by suitable means such as described in connection with the first drum.

The various rotary hide supporting and treating members of the apparatus previously de-

scribed may be driven or actuated in any suitable manner. While the several driven members may be actuated by one or more sources of power through suitable connections, individual motors are preferably provided for the rotary treating devices to facilitate automatic actuation of the cutters. The cutters 19, 20, 45 and 46 may be driven by individual electric motors 42 and the grip rolls 25 and 47 by similar motors 42a, the motors being connected to the members by flexible shafts or, as illustrated, mounted on the journal housings 28 carrying one end of each of the rotary members, those driving the cutters preferably being wired in the control circuit 37. Depending on their range of speeds such motors may be connected directly or through gearing to the shafts of the rotary members. While the relative size of the two work-supporting drums 3 and 4 may vary over a wide range, depending upon the treatments to be applied, they will normally have the same peripheral speeds to facilitate transfer of a hide from the first to the second drum. In such case they may be intergeared, as illustrated, by the gears 52 and 52a, and driven from a single source of power, not shown, through a suitable pulley 53 or like arrangement. The conveyors 5 and 49 may be driven at the desired speeds either by individual motors or, by using suitable power connections, through either or both of the drums. The peripheral speeds of the cutters and grip rolls relative to those of the drums will vary with the type of hide being treated. Normally the surface or peripheral speeds of the grip rolls will be substantially the same as those of the drums, while the cutters will be driven at a considerably higher speed.

With the relative flexibility of its various elements the hide treating apparatus can handle automatically hides of a variety of types and conditions. However, this flexibility is preferably increased by providing for the substitution of parts of different characteristics as well as for any repairs or replacements. To simplify such adjustment the supports 2 of the frame 1 are made in two parts or sections 2a and 2b, each mounting one of the drums 3 and 4 and its associated treating devices. The upper sections 2b are removably seated on the lower sections 2a such that the second drum and its associated parts can be removed as a unit and replaced as desired by a like or different unit. For change of individual parts the ends of the drums may be carried by bearing plates 54 removably attached to the upper and lower sections of the frame, their removal providing a central opening through which the drums and other rotating parts can be withdrawn. The use of a two-part frame also provides a ready means for varying the spacing or clearance between the drums to accommodate hides of different thickness by interposing spacers or shims 55 between the upper and lower sections of the frame.

The hide treating process in its entirety and the relation between the various parts of the apparatus are illustrated schematically in Figure 9. As there shown, a hide 8 is introduced into the apparatus through the feed conveyor 5 from which it is transferred to the first work-supporting drum 3. The latter, gripping the flesh surface of the hide by vacuum, turns counterclockwise and in process carries the leading edge of the hide freely past the station of the first cutter 19 and into the path of the beam of the first photoelectric cell 34, interrupting the

latter. The hide is then engaged by the grip roll 25 by which it is spread and fed toward the station of the second cutter 20. As the hide approaches the second cutter station it interrupts the beam of the second photoelectric cell 35 operating the cutter actuating means, closing the control circuit 37 and causing both cutters to move in and begin treating the grain surface of the hide. This treatment continues until the trailing edge of the hide passes the first photoelectric cell 34, restoring the beam of the latter and thus breaking the circuit and causing the cutters to stop and move away from the surface of the hide. During this period the grain surface of the hide is also subjected to the high pressure fluid jets 44a issuing from various nozzles 44, the jets cooperating with the cutters to un-hair and scud the entire hide.

Past the station of the second cutter the leading edge of the hide approaches the second work-supporting drum 4. As the hide reaches the critical area adjacent the point of convergence of the two drums, suction is cut off from that part of the surface of the first drum 3 and the leading edge of the hide is section-gripped by the second drum. In the process of transfer the surfaces of the hide exposed are reversed, the cleaned grain surface being gripped against the face of the second drum and the flesh surface exposed to the associated treating devices. Rotating clockwise, the second drum carries the hide through its several work-gripping and treating stations where excess flesh is removed in a manner similar to that described for cleaning the grain surface of the hide. After the leading edge of the hide has been carried past the fourth cutter 46 it is brought to the discharge conveyor 49 by which it is led from the apparatus. The hide with the four beam-house operations completed in one pass through the apparatus is then ready for such further processing as may be desired.

Described in application to the performance of beam-house operations on a hide, it will be evident that the apparatus of the present invention is also applicable to the performance of additional or different treatments on hides and to the processing of other sheet material. Thus, on hides, the arrangement, type, size, number or other characteristics of both work-supporting drums and their associated mechanisms can be varied as necessary and the fluid jets can be employed to impregnate the hides with tannages, dyes, cleaning fluids, dehydrates or the like in place of or in addition to their described functions.

From the above detailed description of the invention it will be apparent that there has been provided improved apparatus for treating sheet material which is adapted particularly to the application of a series of treatments to both sides of the material as a continuous operation. While the invention has been described with particular reference to the treating of hides, it will be understood that the described and disclosed embodiments are merely exemplary of the invention and that all modifications, both in the form of the apparatus and its application, are intended to be included as do not depart either from the spirit of the invention or the scope of the appended claims.

Having now described my invention, I claim:

1. Apparatus for treating individual sheets of material, comprising a plurality of work-supporting drums arranged in sequence, means as-

sociated with each of said drums for treating said material, means for gripping said material to the exterior of each of said drums, said means being adapted to present an entire surface of said material to the associated treating means, and means enabling said material to be transferred from one to the next of said drums.

2. Apparatus for treating individual sheets of material, comprising a plurality of movable work supports, means for gripping the inner face of said material on the surface of each of said supports and exposing the entire outer face of said material, means enabling said material to be transferred in sequence from one to the next of said supports, and means associated with said supports for treating said material during its travel through said apparatus.

3. Apparatus for treating individual sheets of material, comprising a plurality of work-supporting drums adapted in sequence to receive and support said material, means associated with each of said drums for treating said material, and means acting on a face of said material for gripping said material to each of said drums, said means being constructed and arranged to enable each of said drums to present an entire surface of said material to said treating means.

4. Apparatus for treating individual sheets of material comprising a plurality of work-supporting drums, means associated with said drums for treating said material, and means for gripping said material to each of said drums and presenting an entire surface of said material to said treating means, said gripping means being constructed and arranged to enable said material to travel through said apparatus in a continuous path with the same edge in the lead.

5. Apparatus for treating hides comprising a pair of work-supporting drums, means associated with each of said drums for treating a hide, said drums being adapted to receive said hide in sequence and each present an opposite face of said hide to said treating means, and means for gripping said hide to each of said drums, said means being constructed and arranged to enable the opposite faces of said hide to be treated in their entireties in a single pass through said apparatus.

6. Apparatus for treating hides comprising a plurality of hide-supporting drums arranged to receive and support a hide on their surfaces in sequence, means associated with said drums for treating said hide, means for gripping said hide to each of said drums in treating means confronting position, and means enabling said hide to be transferred from the surface of one drum to that of the next succeeding drum regardless of the portion of the surface of the first drum occupied by said hide.

7. Apparatus for treating hides comprising a plurality of work-supporting drums, arranged in sequence, means associated with each of said drums for treating a face of said hide, means associated with each of said drums for uniformly gripping the entire hide to the surface of said drums, and means enabling said hide to be transferred from one drum to the next succeeding drum.

8. Apparatus for treating hides comprising a hide-supporting drum, means associated with said drum for treating said hide, means for gripping said hide to said drum in treating means confronting position, and means operated by said hide for actuating said treating means in timed relation to the travel of said hide over said drum.

9. Apparatus for treating sheet work comprising a rotary work-supporting drum, a plurality of devices associated with and positioned in spaced stations along said drum for treating said work, and means operated by said work for causing said treating means to treat said work in timed relation to the travel of said work through said treating stations.

10. Apparatus for treating hides comprising a plurality of work-supporting drums, said drums being arranged to receive and support a hide in sequence, rotary means associated with said drums and adapted to engage said hide, and high pressure fluid jet means associated with said drums, said jet means being constructed and arranged to apply fluid jets under high pressure sufficient to penetrate said hide and sever natural and foreign matter therefrom, said rotary means and jets cooperating to treat said hide.

11. Apparatus for treating hides comprising a plurality of work-supporting drums adapted to receive and support a hide in sequence and expose opposite faces thereof for treatment, and high pressure fluid jets associated with each of said drums and directable against said hide for severing and removing natural matter from said opposite faces of said hide.

12. In an apparatus for removing excess matter from hides a plurality of work-supporting drums arranged to receive and support a hide, said drums sequentially engaging opposite faces of said hide, and fluid pressure means associated with each of said drums and constructed and arranged to apply fluid jets to the confronting surface of said hide under sufficient pressure to remove all undesired natural and foreign matter therefrom.

13. Apparatus for treating hides comprising a plurality of work-supporting drums, said drums being arranged to receive and support a hide in sequence, vacuum means associated with each of said drums for uniformly gripping a hide to its work-supporting surface, and means for releasing the gripping action of said vacuum means on one of said drums adjacent its place of convergence with the next succeeding drum.

14. Apparatus for treating hides comprising a plurality of rotary work-supporting drums, said drums being arranged to receive and support a hide in sequence, means for gripping said hide to the work-supporting surface of each of said drums, rotary cutters spaced around the periphery of each of said drums and normally removed therefrom, said cutters being adapted to extend substantially across the work-supporting face of their associated drum, means for causing said cutters to engage and treat said hide, and means for distributing the pressure applied by said cutters equally over the surface of said hide.

15. Apparatus for treating hides comprising a plurality of rotary work-supporting drums, said drums being arranged to receive and support a hide in sequence as it travels through said apparatus, with adjacent drums engaging opposite faces of said hide, suction means for gripping said hide uniformly to each of said drums, a plurality of treating devices associated with each of said drums and stationed in spaced relation around the periphery of said drum, and means actuated by said hide for causing said treating devices to act upon said hide in timed relation to the travel of said hide over each of said drums.

16. Apparatus for treating hides, comprising a plurality of rotary work-supporting drums, said drums being arranged to receive and support a

hide in sequence as it travels through said apparatus, a plurality of rotary working tools associated with each of said drums and stationed in spaced position around the periphery thereof for treating said hide, said tools being reciprocable radially of and normally spaced from the associated drum, and means for moving said tools into and out of engagement with said hide in timed relation to the travel of said hide around said drum.

17. Apparatus for treating hides comprising a plurality of rotary work-supporting drums arranged to receive and support a hide in sequence, each of said drums having a resilient perforate work-supporting surface, a plurality of rotary devices associated with each of said drums and stationed in spaced positions around the periphery thereof for treating said hide, said rotary devices being adapted to extend substantially across their respective drums, means for applying sub-atmospheric pressure to the interior of each of said drums for gripping and presenting an entire surface of said hide to said treating devices, and means actuated by said hide for causing said devices to treat simultaneously different portions of said hide.

18. Apparatus for treating hides, comprising a rotary work-supporting drum, a plurality of rotary working tools associated with said drum and stationed in spaced positions around the periphery thereof for treating a hide supported on said drum, said tools being normally spaced from and reciprocable substantially radially of said drum, actuating means for reciprocating and rotating said tools, photoelectric cells adjacent said tool stations and adapted to be tripped by said hide, and means connecting said photoelectric cells to said actuating means for causing said tools to treat said hide in timed relation to the travel of said hide around said drum.

19. Apparatus for treating hides comprising a plurality of work-supporting drums, said drums being arranged to receive and support a hide in sequence, vacuum means associated with each of said drums for gripping a hide by suction to its work-supporting surface, and means rendering ineffective the suction on the surface of one of said drums adjacent its place of convergence with the next succeeding drum, thereby enabling said hide to be transferred to said succeeding drum.

20. Apparatus for treating hides comprising a plurality of drums arranged to receive and support a hide in sequence, sub-atmospheric pressure means associated with each of said drums for gripping said hide by suction to the exterior surface thereof, means for feeding said hide to said first drum and removing said hide from said last drum, and means for rendering ineffective the suction over portions of the exterior surfaces of said drums to enable said hide to be transferred successively from each of said drums to the next succeeding drum and from said last drum to said removing means.

21. Apparatus for treating hides comprising a plurality of drums arranged to receive and support a hide in sequence, sub-atmospheric pressure means associated with each of said drums for gripping said hide by suction to the exterior surface thereof, means associated with said drums and operated by said hide for treating said hide in timed relation to its travel over said drums, means for feeding said hide to said first drum and removing said hide from said last drum, and means for rendering ineffective the suction over portions of the exterior surfaces of said

drums to enable said hide to be transferred successively from each of said drums to the next succeeding drum and from said last drum to said removing means.

22. Apparatus for treating hides comprising a plurality of work supports arranged to receive and support a hide in sequence, sub-atmospheric pressure means associated with each of said work supports for gripping said hide by suction to the exterior surface thereof, means for feeding said hide to said first work support and removing said hide from said last work support, and means for rendering ineffective the suction over portions of the exterior surfaces of said work supports to enable said hide to be transferred successively from each of said work supports to the next succeeding work support and from said last work support to said removing means.

23. Apparatus for treating individual sheets of material comprising a rotary work-supporting drum, a plurality of rotary means positioned in spaced stations along said drum, and reciprocable substantially radially thereof for treating said work, and means operated by said work for causing said treating means to treat said work in timed relation to the travel of said work under said rotary treating means.

24. Apparatus for treating hides, comprising a plurality of hollow work-supporting drums arranged in sequence, each of said drums having a perforate work-carrying wall, said wall being multi-layered, the inner of said layers being formed of relatively rigid material, the work-engaging layer being formed of relatively hard resilient material, and the portion of said wall intermediate said inner and outer layers being formed of relatively soft resilient material, each of said drums being adapted to exert a gripping force at its outer surface on application of sub-atmospheric pressure to the interior thereof, and fluid pressure means on one of said drums for neutralizing said force over a predetermined area of its outer surface and enabling said hide to be transferred to the succeeding drum.

25. Apparatus for treating individual sheets of material, comprising a plurality of work-supporting drums arranged in sequence, means consisting of fluid jets associated with each of said drums for treating said material, means for gripping said material to the exterior of each of said drums, said means being adapted to present an entire surface of said material to the associated treating means, and means enabling said material to be transferred from one to the next of said rolls.

55

26. Apparatus for treating individual sheets of material, comprising a plurality of work-supporting rolls adapted in sequence to receive and support said material, means consisting of fluid jets associated with each of said drums for treating said material, and means acting on a face of said material for gripping said material to each of said rolls, said means being constructed and arranged to enable each of said rolls to present an entire surface of said material to said treating means.

27. Apparatus for treating hides having grain and flesh surfaces, comprising a plurality of work stations, means for treating the entire grain surface of a hide in a single pass at one of said work stations, means for transferring said hide to another work station, and means for treating the entire flesh surface of said hide at said second work station.

ROBERT H. GRIFFIN.
